MACHINE FOR MAKING SHOES

Thomas S. Newcomb, Rochester, N. Y.

Application April 25, 1941, Serial No. 390,375

3 Claims. (Cl. 12—7)

This invention relates to machines for use in the manufacture of shoes and more especially to a lasting machine provided with means for cementing the edge of the upper over the edge of the insole in the completion of the lasting operation.

Another object of this invention is to provide an apparatus with which the upper may be quickly and efficiently attached to the insole in a novel manner.

These and other objects and attendant advantages of this invention will become more readily apparent from the detailed description thereof which follows, reference being had to the accompanying drawings in which

Figure 1 is a top plan view of the apparatus embodying my invention.

Figure 2 is a vertical sectional view of the apparatus, the section being taken on the line 2—2 in Figure 1.

Figures 3, 4 and 5 each illustrate a section of the apparatus showing the members of the apparatus in the consecutive positions in which they perform their function in the attachment of the upper to the insole.

The subject matter of the present application is a continuation in part of application Serial No. 291,727 filed August 24, 1939, and, except for the members which perform a new function and provide for the novel operation of the apparatus, the construction of both apparatus is substantially the same.

As illustrated in the drawings, the apparatus includes a bed plate 1 which has the last supporting members 2 and 3 suitably supported for vertical adjustment in the open center thereof. The top of the bed plate is channeled transversely to provide runways for the opposing slides 4, 4 which carry the lasting side wipers 5, 5 at the top thereof. In a runway 6 extending longitudinally at one end of the bed plate is mounted the slide 7 which carries at the top the toe wiper 8. A fixed lasting wiper 9 is mounted at the other end of the bed plate and completes the wiping elements which are adapted to embrace and operate on the upper of the shoe during the lasting operation.

The slides 5, 5 and 7 which carry the side wipers and toe wiper respectively are simultaneously operated on the movement of the slide 7 by means of any suitable operating mechanism such as, for example, is illustrated in the prior application above referred to. As illustrated in Figure 1, the slide 1 has attached thereto the operating rods 1A, 1A which extend longitudinally

in the bed plate to have the pins 7B, 7B carried thereby engage the cam slots 10, 10 in the slides 5, 5. The cam slots 10, 10 are so arranged that endwise movement of the slide 7 causes a simultaneous transverse movement of the slides 5, 5 toward and away from each other so that the side wipers carried thereby simultaneously move in and out with the toe wiper 8.

The toe wiper is provided with the extensions 8A, 8A which project under the ends of the side wipers and bridge the space between the side wipers and the toe wiper so as to provide a continuous outline between them in any position of these wipers and during the movement thereof. As illustrated in Figure 1, the edges of the wipers in their movement contract the opening which they form from that outlined by the solid line to that of the dotted line and, as hereinafter pointed out, perform their function during this movement.

The arms 12, 12 which are mounted to swing on the bed plate 1 support the holding plate 13 between them. This holding plate has a hole 13A therethru the size of and outline of substantially the bottom of the last. The arms 12, 12 are pivoted so as to align this hole with the opening formed by the lasting wipers when the holding plate is swung in place over the wipers from the full line position to the dotted line position illustrated in Figure 2.

Mounted to swing over the holding plate when the latter is placed over the lasting wipers is a clamping mechanism which is supported by the overhanging arm 14. This arm is supported by the upright 15 which in turn is pivoted in the bed plate with provision for a limited swinging movement of the arm 14 from the full line position to the dotted line position in Figure 2. The clamping mechanism carried by the arm 14 comprises a pair of vertically spaced plates 16 and 17 of which the upper plate is yieldingly suspended from the arm 14 and is adapted to be forced away from the arm in a straight line movement by means of the rocking cam 18. The latter is pivoted at 19 and by swinging the handle 20 toward the pivotal support of the arm 14, the plate 16 is forced downwardly by the cam 18 away from the arm 14. A pair of pressure pins 21, 21 project from the bottom of the plate 16 thru the plate 17 for a purpose which will presently appear.

The lower plate 17 is movably suspended from the upper plate 16 by the bolts 23, 23 with suitable springs 24, 24 interposed between them so as to

yieldingly resist the movement of the upper plate toward the lower plate.

In the operation of the apparatus the upper of the shoe is placed between the lasting wipers with the heel of the upper against the fixed heel wiper and the back stay engaging into the notch 22 in the heel wiper so as to properly locate the upper relative to the lasting wipers. The free edges of the upper which have been previously coated with a suitable cement are then folded out and over the edge of the wipers so as to have the cement coated surface face upward on the wipers as illustrated in Figure 2. The holding plate 13 is swung in place over the wipers to hold these outturned edges of the upper in place on the wipers with the upper held suspended in the open center of the bed plate.

As illustrated in Figure 3 the last 25 is then inserted thru the opening in the holding plate which is just large enough to permit the last to pass therethru into the upper. Inserted with the upper or placed over the bottom of the last after it has been inserted into the upper is an insole 26 the edge of which is coated with a suitable cement for the attachment of the insole to the upper as will hereinafter be described.

After the insertion of the last and insole, the clamping mechanism is swung over the holding plate and then operated to have the plate 17 rest on the holding plate and then yieldingly pressed thereagainst by the movement of the plate 16 toward the plate 17 while the pressure pins engage the insole and force the insole and with it the last into the upper until the top of the last rests on the last supporting members 2 and 3, all as illustrated in Figure 4.

With the last thus held in place in the upper and the outturned edges of the upper held clamped between the lasting wipers and the holding plate, the wipers are operated to move inwardly to wipe the outturned edges of the upper from under the clamping plate over the edge of the insole. This causes the cement coated edge of the upper to gradually fold over the cement coated edge of the insole until finally the edge of the upper is completely turned in over the edge of the insole and held in place thereover as illustrated in Figure 5. The two cement coated edges of the upper and the insole are thus brought together to provide a strongly cemented joint between them in the completion of the lasting operation.

As shown in the figures the edges of the upper are preferably skived which makes them more pliable and facilitates the turning of these edges from their outturned to their inturned position. Skiving, furthermore, thins the edges on the outside and thus causes the inturned edge to lie practically flush with the insole to avoid the formation of a pocket centrally of the insole.

After the lasting operation is completed as above described, the clamping mechanism, the holding plate and the lasting wipers are returned to their starting position illustrated in Figure 1

so as to permit the removal of the lasted upper for the attachment of an outer sole and completion of the shoe.

I claim:

5. 1. In a lasting machine having a bed plate with an open center, a toe lasting wiper movable lengthwise and side lasting wipers movable widthwise of the bed plate and arranged to support the outturned edges of an upper within the open center of the bed plate; the combination of means for yieldingly holding the outturned edges of the upper on said wipers with a last located within the upper and an insole on the bottom of the last, and means for operating said wipers to move 15 and draw the outturned edges of the upper around the bottom of the last and then cause these edges to slide completely from under the yielding holding means out of contact therewith and turn in the edges of the upper over the edge of the insole 20 on the last below the wipers on the continued movement of the wipers and thereafter hold the inturned edges of the upper completely against the insole for adhesive attachment thereto.
2. In a lasting machine having a bed plate with 25 an open center, a toe lasting wiper movable lengthwise and side lasting wipers movable widthwise of the bed plate and arranged to support the outturned edges of an upper within the open center of the bed plate; the combination of a movable plate having an opening therethru adapted to move in place over the outturned edges of the upper so as to provide for the insertion of the last and insole into the upper thru said opening, means for yieldingly forcing said 35 plate against the outturned edges of the upper, means for operating said wipers to move and draw the outturned edges of the upper around the bottom of the last and then cause these edges to slide from under the movable plate and turn in over 40 the edge of the insole on the last below the wipers on the continued movement of the wipers, and means for holding the last in the upper during the operation of said wipers in turning the outturned edges of the upper over the edge of the 45 insole supported on the last from under the movable plate.
3. In a lasting machine having a bed plate with an open center, a toe lasting wiper movable lengthwise and side lasting wipers movable widthwise of the bed plate and arranged to support the outturned edges of an upper within the open center of the bed plate; the combination of a movable plate adapted to move in place over the outturned edges of the upper, means for yieldingly forcing said plate against the outturned edges of the upper, means for operating said wipers to move and draw the outturned edges of the upper around the bottom of the last and then cause these edges to slide from under the movable plate and completely turn in over the edge portion of the insole on the last on the continued movement of the wipers, and means for holding the last in the upper during the operation of said wipers.

THOMAS S. NEWCOMB.
